(57) **CLAIM**

The ornamental design for a rodent trap as shown and described.

DESCRIPTION

FIG. 1 is a perspective view of a rodent trap according to the new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded perspective view thereof, showing an upper portion of the rodent trap separated from a lower portion thereof.

The broken lines represent portions of the rodent trap that form no part of the claimed design. The rodent trap is shown with a symbolic break in its length. The appearance of any portion of the article between the break lines forms no part of the claimed design.
